(57) **CLAIM**

The ornamental design for a jar opener, as shown and described.

DESCRIPTION

FIG. 1 is a first perspective view of a jar opener showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 2.

The broken lines shown in the drawings depict portions of the jar opener that form no part of the claimed design. The

(Continued)

dot-dash broken lines in the drawings are included for the purpose of depicting the partial enlarged views and form no part of the claimed design.

1 Claim, 10 Drawing Sheets
